M. O. ANTHONY

PIN TICKET

Filed July 7, 1921

Inventor,
Marcus O. Anthony,
By *N. J. Bernhard*
Attorney,

UNITED STATES PATENT OFFICE.

MARCUS O. ANTHONY, OF NEW YORK, N. Y.

PIN TICKET.

Application filed July 7, 1921. Serial No. 482,895.

To all whom it may concern:

Be it known that I, MARCUS O. ANTHONY, a citizen of the United States, residing at the city of New York, county and State of 5 New York, have invented a certain new and useful Pin Ticket, of which the following is a specification.

This invention is a ticket for use on merchandise or goods of various kinds in order 10 to attach thereto means for indicating data, such as the sales and costs price, style, grade, etc.

The invention pertains, more particularly, to that kind of tickets provided with attaching means in fixed relation to the ticket proper, a familiar form of which attaching means is a double pointed or staple-like pin the prongs of which pass through apertures of the ticket and are insertible into the 20 goods or merchandise, after which insertion the prongs or legs of the staple are bent.

It is well known to those skilled in the art that double pointed pins, or staple like pins, are characterized by sharpened points 25 rendered more or less rough by the presence of burs or fins which are produced in the operation of cutting off the double pointed pin from a length of wire, as a result of which the sharp points are liable to prick the fingers of the operator in inserting or removing the pin ticket and, further, the rough edges at the points will catch and tear delicate fabrics, and the pins are further objectionable for the reason that the ticket attached 30 to one article catches in other articles adjacent thereto.

Prior to my invention it has been proposed to overcome the foregoing and other objections by the provision of a double 40 points or staple like attaching member characterized by a form of construction wherein each prong or leg is composed of two strands of wire the doubled end of which presents a smooth rounded point free from burs.

According to my present invention I produce an attaching and penetrating member in the form preferably of a double pointed pin each leg of which consists of a single strand the point of which is rounded and 50 the opposite faces of which are flattened so as to produce a pin which is tapering in longitudinal section by reason of the converging relation of the inclined flattened faces and the point of which is rounded and 55 free from burs or projections. The double

pointed pin of this invention is distinctly novel with respect to the formation of the points of each leg of the pin, the desired effect being obtained by subjecting the metal to the action of appropriate dies or rolls in 60 a manner to flatten and taper the point and to round the extremity of the pin, whereby economy in manufacture is obtained owing to the use of a single strand of material and the attaching member is provided with smooth rounded points on the two ends of the attaching member, said smooth pointed pins being easily thrust into and through the fabric by separating the fibres thereof and said smooth pointed pins being manipulated 70 without danger of pricking the fingers.

Other functions and advantages of the invention will appear from the following description taken in connection with the drawings, wherein—

Fig. 1 is a perspective view of a pin ticket embodying this invention.

Fig. 2 is a view of the length of wire material prior to treatment for the production of my attaching member.

Figs. 3 and 4 are views in plan and side elevation illustrating the wire material after treatment to produce the smooth and rounded points on the pin in accordance with the invention.

Fig. 5 is a perspective view of a complete attaching member removed from the ticket.

The article comprises a ticket A and an attaching member B, the former being composed of cardboard, paper or other material 90 suitable for the purpose.

The member B is composed of metal, preferably wire in the form of a single strand, the same being bent to produce a plurality of pins a b and a base c. As shown, the wire is first bent to produce a loop d and thereafter bent so as to obtain members e f, the two ends of the wire forming the pins a b. In the form of the base c, the loop d thereof is in contact with the reverse face of the ticket, the members e embrace the edge of said ticket, whereas the members f are in contact with the face of said ticket, it being understood that the double pins a b pass through the apertures g in said ticket. The described form of base c performs the function of clamping the double pointed pin to the ticket so as to fixedly attach the pin thereto, but although I have shown and described one form of said base c it is to be 110

understood that the new double pointed pin may be modified in respect to the means for fixedly attaching said pin to the ticket.

The attaching member is composed of a single strand of wire, no part of said member, and particularly the plurality of pins being characterized by a doubled construction of wire.

One mode of producing the attaching member involves the use of wire material C, the same comprising a strand of the appropriate length and diameter, see Fig. 2. This strand is subjected to treatment whereby each end portion is flattened on its opposite faces at 5, 6, and the extremity is rounded at 7, see Figs. 3 and 4. The flattened faces are inclined to each other and converge toward the extremity so as to result in a sharpened edge, but this edge is not pointed for the reason that it is rounded at 7. The end portion of each pin is thus tapered by beveling the same on opposite faces and is rounded to produce a penetrating point the surfaces of which are smooth and free from burs. The metal is subjected to pressure in suitable dies, rolls, or other mechanical appliances suitable for the purposes of compressing the material laterally and rounding the extremity thereof, the effect of which is to displace the metal in a manner to elongate it somewhat while fashioning it to produce the desired effect. The opposite end portions of the metal are each compressed to flatten and taper the faces and to round the extremities, the part of the metal intermediate the treated end portions being bent to produce the pins *a* *b* and a desired form of base whereby the resulting double pointed pin is adapted for attachment to a suitable ticket.

The attaching member constructed in accordance with my invention is characterized by a double pointed pin each prong of which is peculiarly formed to produce a smooth tapering and rounded edge adapted to easily pass through the fabric by displacing the fibres thereof, said edge being free from a sharpened point so that it cannot prick and injure the fingers nor will it

catch in the goods for the reason that the surfaces of the double pointed pin are smooth and free from burs.

Having thus fully described the invention, what I claim as new, and desire to secure by Letters Patent is:

1. A pin ticket characterized by a pin provided on its opposite faces with bevels converging toward the extremity of said pin so as to impart a longitudinal taper to the end portion, said extremity being provided with a rounded edge. 60

2. In a pin ticket, a double pointed pin composed of a single strand of wire and comprising a plurality of prongs each of which is a single wire, each of said single wire prongs being provided on two faces only thereof with bevels which converge toward, and meet each other at, the extremity of said prong, and said extremity being characterized by a rounded edge which merges into parallel edges that define in part the longitudinal contour of said wire strand. 65

3. In a pin ticket, a double pointed pin each prong of which is composed of a single length of wire the extremity of which is provided with a rounded smooth edge, said prong being provided with bevels on opposite faces thereof and said bevels converging toward the rounded edge of the prong. 70

4. In a pin ticket, a pin the extremity of which is formed by a rounded smooth edge, the material composing said pin being compressed to produce on opposite faces thereof a plurality of bevels which converge toward said rounded edge. 75

5. In a pin ticket, a pin comprising a single strand of material the extremity of which is formed by a rounded smooth edge, said material being compressed adjacent said rounded edge for imparting a taper to the pin and producing on opposite surfaces thereof bevels which converge toward the rounded edge. 80

In testimony whereof I have hereunto subscribed my name.

MARCUS O. ANTHONY.
